UNITED STATES PATENT OFFICE.

FRANK CASPER MAYER, OF BRIDGEVILLE, PENNSYLVANIA.

TIE FOR MINE-RAILWAYS.

1,359,413.

Specification of Letters Patent. Patented Nov. 16, 1920.

Application filed July 30, 1920. Serial No. 400,118.

To all whom it may concern:

Be it known that I, FRANK C. MAYER, a citizen of the United States, and a resident of Bridgeville, in the county of Allegheny 5 and State of Pennsylvania, have invented a new and Improved Tie for Mine-Railways, of which the following is a full, clear, and exact description.

This invention relates to railway track 10 appliances and has particular reference to railways for mines, tram cars, or other railways of a relatively temporary nature as distinguished from standard heavy traffic, such as steam or electric railways. 15 Among the objects of the invention is to provide a new type of railway ties the same being applicable especially for making a reliable joint between metal and wooden rails. 20 Another object of the invention is to provide a railway tie adapted for the direct application thereto of either metal or wooden rails.

With the foregoing and other objects in 25 view the invention consists in the arrangement and combination of parts hereinafter described and claimed, and while the invention is not restricted to the exact details of construction disclosed or suggested here- 30 in, still for the purpose of illustrating a practical embodiment thereof reference is had to the accompanying drawings, in which like reference characters designate the same parts in the several views, and in 35 which—

Figure 1 is a plan view of one end portion of my improved tie showing secured thereto the meeting ends of metal and wooden rails.

40 Figs. 2 and 3 are vertical transverse sections on the corresponding lines of Fig. 1.

Fig. 4 is a vertical transverse section of the tie alone on the line 4—4 of Fig. 2.

Referring now more specifically to the 45 drawings I show my tie 10 as comprising a main body portion shown as flat but obviously capable of being made of any suitable design in cross section. This tie may be made of any suitable material, but 50 I have found for the best practice that malleable iron is quite suitable, being relatively cheap and of a strong tough nature. Such material also lends itself immediately for the making of the special features constituting attachment means for the rails. While I show but one end

of the tie it will be understood that each tie will be made complete as a unit with similar ends for the attachment of rails at the usual distance apart, and while 60 I show and describe but one series of attachment means for the rails such description will be understood as being applicable to both ends of the tie.

11 indicates a pair of spurs carried by the 65 upper surface of the tie and adjacent to the edges thereof. These spurs are notched or undercut at 12 at one side to receive one edge of the base flange 13 of a metal rail 14. The spurs are so located as to automatically 70 establish the proper position for said rail with respect to the tie and the rail at the opposite end of the tie. These spurs are arranged in pairs and similarly located with respect to the end of the tie and being in 75 pairs they are adapted for coöperation with the meeting ends of two adjacent rails, but if a single rail spans the tie the presence of the two spurs is no objection but rather an advantage in favor of strength. The upper 80 ends or points of the spurs are somewhat sharpened.

The tie 10 is provided with holes 15 preferably arranged one for each spur 11 and at about the same distance from the edge of 85 the tie. These holes 15 are located on the opposite side of the line of the rails 14 from the spurs, and for the clamping of a metal rail to the tie in connection with a spur 11 I employ a clamping block 16 in 90 connection with a bolt 17, or its equivalent, passing upward through a hole 15 and through said block. Each block 16 is provided with a square end 16^a while the other end 16^b is somewhat longer than the square 95 end and conforms to the side of the metal rail and having an undercut 16^c to accommodate the edge of the base flange opposite the one projecting beneath the spur 11. The block 16 being of considerable width and 100 fitting squarely against both the base flange and the web of the rail is held securely from rotation around the bolt 17 when the nut 17' of the bolt is tightened. Consequently any endwise shifting of the rail 14 105 would tend to be resisted by the cramping of the block in addition to the normal frictional contact between the rail and all of the parts coöperating therewith.

18 indicates a wooden rail such as is 110 commonly used in mines or other temporary track structures. In the usual practice it is

a difficult matter to secure the abutting end of a wooden rail in place to constitute a continuation of a metal rail. With my improvement, however, such attachment of a wooden rail is both expeditious and reliable. To this end I provide a flange 19 shown as constituting a rigid or integral part of a tie between the extreme end thereof and the spurs. This flange is parallel to the line of the rails and is provided preferably with an inner surface perpendicular to the top surface of the tie. The outer surface of the flange may be inclined or battering for the sake of maximum strength. The flange, however, is provided with a plurality of holes 20 the axes of which are perpendicular to the rails and parallel to the tie. The rail 18 as usually made and used is of the same height as the metal rail, but is somewhat wider giving a maximum degree of firmness and strength. The width of the rail 18 corresponds approximately to the spacing of the flange 19 or in practice the rail 18 may be either reduced or increased in width to establish the proper alinement of the rails. Each hole 20 is adapted to receive a spike 21 which may be driven through the hole and into the side of the wooden rail remote from the line of the metal rail. The bottom of the rail 18 receives the spur 11. This may be provided for either by notching or recessing the rail at 18', or the same result may be accomplished by simply placing the rail on top of the spike and striking down upon the rail with a sledge causing the spur to be driven relatively upward into the rail. Thus the spur or spurs will serve to substantially hold the wooden rail from endwise movement. Lateral movement of the rail 40 toward the end of the tie is prevented by the flange 19. The lifting of the rail is prevented by the spike or spikes 21. Movement of the rail away from the flange or toward the center of the tie is prevented by means 45 of the block or blocks 16 applied with their square ends 16' squarely against the inner vertical side of the rail. See Fig. 3. The blocks 16 being made preferably all alike so that either end thereof may be employed for 50 gripping contact with a rail, absolute reliability as well as facility in connecting the rails to the ties is assured. From the foregoing description it will be obvious that the same type of ties may be employed for any 55 portion of the road and for the attachment of either all metal rails or all wooden rails, or any desired combination thereof. It is manifest that the ties may be employed for rail joints as well as for supporting any 60 other portions of the rails, and that no fish plates or other attachment means, auxiliary to the devices above described, are required.

I claim:

1. The herein described metal railway tie 65 having a rigid spur projecting upward from

its upper surface adjacent to the line of the rails, a member projecting upward from the tie between the spur and the end of the tie, and clamping means coöperating with the tie upon the opposite side of the spur from 70 the upwardly projecting member.

2. The combination with the abutting ends of a metal and a wooden rail, of a tie for supporting said ends, said tie comprising means to hold the metal rail and means to 75 secure the wooden rail, the securing means for the wooden rail comprising a spur projecting into the bottom of the wooden rail, and means coöperating with both sides of 80 the wooden rail.

3. The combination with the abutting ends of a metal rail and a wooden rail, of a tie for supporting said ends, means carried by the tie to secure the metal rail thereto, and securing means for the wooden rail, the 85 wooden rail securing means comprising members projecting upward into the bottom and inward laterally into one side of the wooden rail and a clamping member co-operating with the opposite side of the 90 wooden rail.

4. A device as set forth in claim 3 in which the means for securing the wooden rail includes a rigid spur carried by the tie and projectable upward into the bottom of 95 the rail, a rigid member bearing against one side of the rail, and a spike driven through said rigid member into the adjacent side of the rail.

5. A device as set forth in claim 3 in 100 which the means for securing the wooden rail includes a flange integral with the tie and projecting upward against one side of the rail, said flange having a hole therethrough parallel to the tie, and a spike projectable through said hole into the adjacent side of the rail.

6. A device as set forth in claim 3 in which the means for securing the rails to the tie includes a plurality of blocks one 110 for each rail and a clamping bolt to secure each block to the tie, the ends of the blocks from the axis of the bolt being unequal in length, but both ends being adapted to abut 115 squarely against the side of the wooden rail 115 or the side of the web of the metal rail respectively.

7. The herein described metal tie having a flat upper surface from which project upward a pair of spurs, the spurs being undercut on the side adjacent to the line of the rails for coöperation with the bottom portions of the rails, a rigid flange projecting upward from the tie between the spurs and the extreme end of the tie and having a flat 120 vertical surface adjacent to the spurs, and the tie being formed with a plurality of holes on the opposite side of the spurs from the flange, substantially as set forth.

FRANK CASPER MAYER.
